C. DRESSLER

SALT GLAZING AND KILN FOR SAME

Filed May 17, 1920

UNITED STATES PATENT OFFICE.

CONRAD DRESSLER, OF CLEVELAND, OHIO, ASSIGNOR TO AMERICAN DRESSLER TUNNEL KILNS, INC., OF NEW YORK, N. Y., A CORPORATION OF NEW YORK.

SALT GLAZING AND KILN FOR SAME.

Application filed May 17, 1920. Serial No. 382,002.

To all whom it may concern:

Be it known that I, CONRAD DRESSLER, a subject of the King of Great Britain, and resident of Cleveland, in the county of 5 Cuyahoga and State of Ohio, have invented certain new and useful Improvements in Salt Glazing and Kilns for Same, of which the following is a specification.

My present invention comprises improvements in construction and mode of operation devised with the specific object in view of firing and salt glazing ceramic ware in a continuous tunnel kiln having firing, glazing and cooling zones formed by communicating sections of an elongated kiln chamber through which the ware is moved.

While my improved method of salt glazing may be carried out in various forms of tunnel kilns I preferably employ for the 20 purpose a muffle kiln of the internal combustion chamber type disclosed, for example in my prior Patents 1,023,628 and 1,170,428. A characteristic feature of this type of kiln is that the heat transfer between the ware 25 and the combustion chambers by which the kiln is heated, is wholly or mainly by a convection current circulation of the kiln atmosphere which is heated by contact with the combustion chambers and imparts heat 30 to the ware and is thereby cooled.

In firing and salt glazing ceramic ware in a continuous tunnel kiln in accordance with the present invention, I maintain a reducing atmosphere containing salt vapors in 35 the glazing zone of the kiln chamber which is intermediate the heating up or main firing zone and the cooling zone. It is highly desirable to prevent any flow of the glazing zone atmosphere into the zones or kiln sections at either side of the glazing zone, because of the detrimental effect of the salt 40 vapors on the combustion chambers in the firing zone and the cooling pipes in the cooling zone, and also because it is desirable to 45 maintain oxidizing atmospheres in these zones.

A second object of the present invention therefore is the maintenance in a continuous kiln of a glazing zone atmosphere which is 50 different from the atmosphere maintained in the kiln sections at either side of the glazing zone. I accomplish this object in a kiln of the special internal combustion chamber type which I preferably employ in salt glazing in part by supplying salt vapors and

reducing gas atmosphere constituents to the glazing zone, and withdrawing vapors and gases thus supplied and not absorbed by the ware, without passing them through the kiln zone at either side of the salt glazing 60 zone. In addition I maintain pressure conditions in the kiln which prevent the glazing zone atmosphere from passing into the kiln zones at either side of the glazing zone by diffusion or by longitudinal flow, but do not 65 materially disturb the convection current circulation in the kiln zones at the sides of the glazing zone. The features of construction and method which I have devised for this purpose may be employed in carrying out 70 other processes than salt glazing in continuous kilns.

The various features of novelty which characterize my invention are pointed out with particularity in the claims annexed to 75 and forming a part of this specification. For a better understanding of the invention, however, and the advantages possessed by it reference should be had to the accompanying drawings and descriptive matter in 80 which I have illustrated and described a preferred form of my improved tunnel kiln.

Of the drawings:

1. Fig. 1 is a somewhat diagrammatic plan in section of a kiln. 85

2. Fig. 2 is a vertical section of a portion of the kiln shown in Fig. 1, taken on the line 2—2 of Fig. 1,

And Figs. 3, 4, 5, 6 and 7 are transverse vertical sections taken respectively, on the 90 lines 3—3, 4—4, 5—5, 6—6 and 7—7 of Fig. 1.

The kiln A shown in the drawings, comprises an elongated chamber of which one end section A¹, serves as a ware heating or 95 main firing zone, intermediate sections A² and A³ serve as a glazing zone, and the other end section A⁴ is a ware cooling zone. The goods enter the kiln at one end of the zone A' past a door B which is normally closed, 100 and leave the kiln at its opposite end past the normally closed door C. As shown the goods are moved through the kiln on trucks E running on track rails DA. The heating zone A' of the kiln is laterally enlarged to 105 provide space for combustion chambers D, one at each side of the pathway for the goods, and for tubular extensions D² of the combustion chambers. The combustion chambers and their extensions rest upon 110

benches A⁵ at the sides of the kiln. The combustion chambers extensions D² are connected at their ends adjacent the door B to headers D³ provided with outlets D⁴ 5 through which products of combustion pass to a flue D⁵ running to a stack or other suitable exhauster not shown. At the opposite end of the heating up zone the combustion chambers are provided with gas burners G' 10 supplied with gas through suitable regulating valves G² from gas supply pipes G. Adjacent each gas burner is an inlet F' for air supporting combustion. Each inlet F' leads from a corresponding air supply tunnel F extending longitudinally of the kiln. The supply of air through each inlet F' is controlled by a damper F². The combustion chambers D and the general arrangement of the heating up zone of the kiln 15 shown is like that commonly employed in the well known Dressler tunnel kiln. It is to be noted however that my invention in some of its aspects is not restricted to the particular kind of muffle heated kiln shown, but may be carried out in open fire kilns as 20 well as in other types of muffle heated kilns.

The glazing zone sections A² and A³ have their roofs slightly higher than the roof of the heating up zone A¹ to provide a gas collecting space of considerable capacity above the goods' pathway. This gas collecting space is divided into compartments A⁷ which are open at their lower ends, by transverse barriers or flat arches A⁸. Each of the compartments A⁷ is provided with one or more stack outlets A⁹ opening through its roof. At each side of the glazing zone sections A² and A³ and in open communication therewith are one or more chambers A¹⁰. As shown the 30 chambers A¹⁰ each receives combustible gas through burner pipes G³ connected to the gas supply pipes G through regulating valves G⁴, and receives air for the combustion of the gas from the tunnel F through a corresponding vertical passage F⁴. Each of the 35 passages F⁴ is provided with a regulating damper F⁵. Salt or other glazing agent to be vaporized by the combustion occurring in the chambers A¹⁰ is supplied to each of the 40 latter through a corresponding pipe K.

Advantageously, as in the particular construction shown, the roof of the cooling zone A⁴ is elevated to provide a series of air collecting compartments A¹¹ open at their lower ends to the goods pathway and separated from one another by barriers or flat arches A^{8'}. The air for cooling the ware passing through the zone A⁴ enters the kiln at its exit end as through ports C' in the door C. The air thus admitted and heated by contact with the goods collects in the various compartments A¹¹ and is withdrawn from each of the latter, except the compartment A¹¹ immediately adjacent the glazing zone 55 of section A³ by a pipe J. The latter runs

along the roof of the kiln and is connected to each of the compartments beneath it. The end of the pipe J, adjacent the glazing zone is connected to the inlet of a fan I. The latter is connected by piping H to two delivery nozzles H¹ opening one into one and the other into the second of the air supply tunnels F. These nozzles draw by an ejector action air too hot to pass the fans I from the compartment A¹¹ immediately adjacent the glazing zone through vertical channels F³ in the side walls of the kiln. Air delivered by the fan I in excess of the burner requirements may be passed to a drier or otherwise disposed of through a branch pipe I¹⁰.

With the apparatus described, trucks are introduced into the kiln one at a time at regular intervals past the door B. As each truck is thus introduced, the train of cars filling the kiln is advanced a car length, and a truck with finished ware thereon is ejected from the exit end of the kiln. Any suitable means may be employed for periodically pushing the cars into the kiln and advancing the train of cars filling the kiln. No means for accomplishing this are shown, as suitable means for the purpose are well known and in common use. As the goods are moved through the heating up zone A¹ of the kiln, the ware is more or less gradually and uniformly brought up to the temperature necessary to completely mature the ware. As shown the ware X is sanitary drain tile stacked two lengths high on the cars, but it will be understood, of course, that the invention is applicable to other ware and other stacking arrangements than that shown. In its passage through the glazing zone section A² and A³ of the kiln, the ware is subjected to the action of the burning gases and vaporized glazing agent passing into the kiln from the chambers A¹⁰. By suitable manipulating of the gas valves G⁴ and the air dampers F⁵, the amount of gas burnt and the composition of the burning gases entering the kiln from the chambers A¹⁰ may be regulated as desired. It is ordinarily desirable to maintain a strongly reducing atmosphere in the glazing zone. This can be done, 100 of course with the apparatus shown by supplying insufficient air to the chambers A¹⁰ for the complete combustion of the gas supplied to those chambers by the burners G³. The gases and vapors admitted to the glazing zone and not absorbed by the ware escape from the kiln through the vents A⁹. The suction exerted by the latter on the glazing zone may be varied by adjusting the dampers A¹¹ applied to the vents A⁹ as 105 shown in Fig. 5. The distributed outlets for the air by which the ware is cooled in the zone A⁴, makes possible a very desirable control of the temperatures in the cooling zone, and the special provision described for passing this air into the tunnel F insures the nec-

115
120
125
130

essary draft out of each of the compartments A' without subjecting the fan to the high temperature of the air in the compartments A' immediately adjacent the high temperature section of the kiln.

The apparatus shown was primarily devised for use in the so called salt glazing process in which the glazing agent employed is common salt, the vapors of which unite with 10 the clay ware at its surface and along surface fissures to form silicate of soda. Salt glazing is particularly desirable because of the excellence of the glaze and the relatively low cost of the glazing agent. The use of 15 such a glazing agent in a continuous tunnel kiln is possible only wherein the kiln construction and operation is such as to prevent the glazing agent from contacting appreciably with the walls of the combustion chambers or other highly heated portions of the 20 kiln structure which would be injured or destroyed by an excessive coating of glazing material. It is highly desirable to prevent the condensation of salt vapors in the cooling 25 zone of the kiln.

To prevent the glazing zone atmosphere from passing into the firing or cooling zones I so regulate pressure conditions in the kiln that there will be a slight but continuous 30 influx of air into the glazing zone from the portions of the kiln chamber at either side of the glazing zone. The air thus withdrawn from the end portions of the kiln may be supplied by leakage around the doors 35 at the ends of the kiln, or by special air inlet ports provided for the purpose. I so regulate the suction through the outlets A' that there is a gentle influx of air into the glazing zone from either end without creating 40 longitudinal air currents through the end portions of the kiln materially modifying the convection current circulation in the end portions of the kiln chamber transversely of the latter. The air gently flowing 45 into the opposite ends of the glazing zone will unite in combustion with the reducing gas in the glazing zone with a resultant production of carbon dioxide. The end portions 50 of the glazing zone atmosphere will thus consist of streams of gas flowing upward to the outlets A' and containing more or less carbon dioxide. The very existence in these end streams of carbon dioxide, tends to retard the combination in combustion of the 55 air in the end portions of the kiln with the reducing gases in the glazing zone atmosphere. In consequence the combustion occurring in regular operation is in no wise explosive in character, and with the small 60 amount of air available, the combustion is relatively insignificant in amount.

While in accordance with the provisions of the statutes, I have illustrated and described the best form of my invention now 65 known to me, it will be apparent to those

skilled in the art that changes in form may be made without departing from the spirit of my invention, as set forth in the appended claims, and that certain features of my invention may sometimes be used to advantage without a corresponding use of other features.

Having now described my invention, what I claim as new and desire to secure by Letters Patent, is:

1. The method of glazing ceramic ware which consists in moving the ware through an elongated kiln chamber, cooling an exit end portion of the kiln chamber and heating other portions thereof as required to glaze 80 fire and then cool the ware in its passage through the chamber, maintaining a reducing atmosphere containing a vaporized glazing agent in a high temperature glazing zone portion of the chamber.

2. The method of glazing ceramic ware which consists in moving the ware through an elongated kiln chamber, cooling an exit end portion of the kiln chamber and heating other portions thereof as required to glaze 90 fire and then cool the ware in its passage through the chamber, supplying a vaporized glazing agent to a high temperature glazing zone portion of the kiln chamber, withdrawing gases and vapors from the last 95 mentioned kiln chamber portion and supplying air to portions of the kiln chamber at each end of said glazing zone portion.

3. The method of salt glazing ceramic ware which consists in moving the ware 100 through an elongated kiln chamber, cooling an exit end portion of the kiln chamber and heating other portions thereof as required to glaze fire and then cool the ware in its passage through the chamber and maintaining an atmosphere containing salt vapors in a high temperature glazing zone portion of the chamber.

4. The method of salt glazing ceramic ware which consists in moving the ware 110 through an elongated kiln chamber, cooling an exit end portion of the kiln chamber and heating other portions thereof as required to glaze fire and then cool the ware in its passage through the chamber, supplying salt vapors to a high temperature glazing zone portion of the kiln chamber, withdrawing gases and vapors from the last 115 mentioned kiln chamber portion and supplying air to portions of the kiln chamber at each end of said glazing zone portion.

5. The method of maintaining different atmospheres in successive communicating zones or sections of an elongated kiln chamber through which material is moved and in which it is mainly heated by convection currents of the kiln atmosphere contacting with the material and with a hot body or bodies at the side of the pathway for the material, which consists in supplying gas- 125 130

- eous ingredients to different zones of the kiln chamber and withdrawing gases from an intermediate one of said zones as required to substantially neutralize the tendency of 5 the atmosphere, in the zone from which the gases are withdrawn, to mix with the atmosphere in an adjacent zone by diffusion or as a result of convection current circulation longitudinally of the kiln.
- 10 6. The method of maintaining different atmospheres in successive communicating zones or sections of an elongated kiln chamber through which material is moved and in which it is heated mainly by convection currents of the kiln atmosphere contacting with the material and with a hot body or bodies at the side of the pathway for the material, which consists in supplying gaseous ingredients to the different zones to 15 form the different atmospheres thereof, withdrawing gases from an intermediate zone of said series, and maintaining pressure conditions in said kilns to prevent appreciable longitudinal gas flow in the kiln 20 chamber.
- 25 7. In a muffle heated kiln the combination with the kiln chamber and muffle heating means therefor, of means for supplying ingredients to an intermediate high temperature of said kiln chamber for maintaining a reducing atmosphere containing a vaporized glazing agent therein, and gas outlets opening through the wall of said chamber to said zone.
- 30 8. In a muffle heated kiln the combination with an elongated kiln chamber and muffle heating means therefor, of combustion chambers opening to the kiln chamber in a high temperature zone thereof intermediate its ends, means for supplying fuel, air and a vaporizable glazing agent to said combustion chambers so as to thereby supply a reducing gas atmosphere containing the 35
- 40 glazing agent in a vaporized form to said zone, and gas outlets opening through the 45 wall of the kiln chamber to the glazing zone portion thereof.
- 45 9. The combination with a tunnel kiln comprising a heating up zone, a cooling zone and an intermediate glazing zone, and having combustion chambers in said heating up zone and cooling conduits in said cooling zone, of combustion chambers opening into the glazing zone portion of the kiln chamber, gas outlets formed in the kiln chamber wall and opening to the glazing zone portion of the kiln chamber, means supplying fuel and a vaporizable glazing agent to the last mentioned combustion chambers, means supplying fuel to the first mentioned 50 combustion chambers, and means for passing air through said cooling conduits into all of said combustion chambers.
- 55 10. A tunnel kiln provided with a main stack or fan and also having an auxiliary 55 stack or fan independent thereof by which special gases and vapors which have been introduced into the kiln for special purposes may be removed therefrom without resort being had to the means for inducing the 60 main draft.
- 65 11. A tunnel kiln provided with a main stack or fan and also having an auxiliary stack or fan independent thereof acting on the firing zone of the kiln whereby special 70 gases and vapors which have been introduced into the kiln for special purposes may be removed from the firing zone without resort being had to the means for inducing the main draft before said gases or vapors 75 have the opportunity of coming in contact with ware in other parts of the kiln.

Signed at Cleveland, in the county of Cuyohoga and State of Ohio this 12th day of May A. D. 1920.

CONRAD DRESSLER.
